DOOR LATCH FOR MINE CARS

Victor Willoughby, Ridgewood, N. J., assignor to
 American Car and Foundry Company, New
 York, N. Y., a corporation of New Jersey

Application March 20, 1940, Serial No. 324,897

12 Claims. (Cl. 105—253)

This invention relates in general to mine cars and in particular to mine cars of the automatic drop bottom type.

In the majority of drop bottom mine cars the doors and latches have been so arranged that the last or rearmost door of the car must swing to an open position before the remaining doors can open. As a result when the car runs over dumping station the coal or other material, dropped through the front or lading door, drops a considerable distance and is badly broken. These cars also are equipped with latch operating mechanism which projects from the side of the car and is frequently bent or broken by striking obstructions in the mines, such as pillars, tunnel walls or fallen rock. It is an object, therefore, of the present invention to provide a mine car of the drop bottom type having automatic latches in which no part of the latches projects beyond the clearance limits of the body alone.

A further object of the invention is the provision of an automatic drop bottom mine car in which a plurality of doors are provided, each held in closed position by latches wholly independent of the latches on the other doors.

A still further object of the invention is the provision of an automatic drop bottom mine car in which latches are provided for the door and which latches have no part thereof projecting beyond the clearance limits of the car body alone.

Yet another object of the invention is the provision of an automatic mine car having the doors opening from front to rear of the car and controlled by latches operable by means located beneath the car and between the track rails.

These and other objects of the invention will be apparent to persons skilled in the art from a study of the following description and accompanying drawings, in which:

Figure 1 is a longitudinal sectional view of a drop bottom car having the improved latches attached thereto;

Fig. 2 is a sectional view similar to Figure 1 but showing the forward end of the car;

Fig. 3 is a slightly enlarged sectional view of one of the improved latches in closed or door retaining position;

Fig. 4 is an end elevation of the improved latch mechanism;

Fig. 5 is a sectional view taken substantially on line 5—5 of Figure 3;

Fig. 6 is a sectional view similar to Fig. 3 but showing the mechanism in door releasing position;

Fig. 7 is an end elevational view of the mechanism shown in released position by Fig. 6;

Fig. 8 is a perspective view of the vertically sliding latch bolt;

5 Fig. 9 is a sectional view showing the latch mechanism for the rearmost door and with the parts in door open position, and

Fig. 10 is an end elevational view of the mechanism shown in Fig. 9.

10 Referring now to the drawings in detail, it will be seen that the doors and latch mechanism have been applied to a more or less conventional car having side sills 2 supported by axles 4 and wheels W. These sills are joined together at the 15 rear end of the car by end structure 6 of any approved type. In the present instance this structure includes a coupling pin 7, wood bumper block 8 and bumper cap 10 connected to an angular form end sill 12. The forward ends of the 20 side sills are connected together by a similar end sill structure 14 which carries a combined spring bumper and draft gear 16. It is obvious, of course, that spring bumper and draft gears or wood blocks may be used at both ends of the 25 car or that other bumper structures can be used. These side sills and end sills form what may be termed a traction truck frame to which is connected the lading retaining side walls 18 and end walls 20 suitably braced by gussets or other 30 devices so placed as to obtain maximum strength.

The side sills are tied together intermediate the end sills by means of axle hood pressings 22 which also serve as protectors preventing material from escaping from the car between the 35 drop bottom doors. The floor of the car is completed by a series of drop bottom doors 24, 25 and 26 located respectively adjacent the front, center and rear of the car. The front door is pivoted on a hinge rod 28 extending between 40 the side sills and is formed like the remaining doors as a pan shaped pressing having side flanges 29, front flange 30 and rear flange 32 which is inclined upwardly and rearwardly beneath the axle hood or other projecting structure and for 45 support upon the improved latch mechanism later to be described. Each of the doors has a corrugation 34 pressed upwardly therein intermediate the side flanges. This corrugation, as clearly shown in Fig. 4, is of inverted channel 50 cross section and extends longitudinally of the door between the rear and front flanges thereof, thus forming in effect a channel reinforcement for the bottom while at the same time providing a longitudinally extending trough running 55 from end to end of the car which will permit

the passage of a tripping ramp R (Fig. 3). The doors are substantially identical with the exception of the middle and rearmost door for larger hinge portions in order that they may be hinged and rotate on the car axle and these doors are also provided with small pressed projections 36 in the forward flange thereof, which projections are of sufficient depth and height as to clear a portion of the latch mechanism now to be described.

The latch mechanisms for the forward and center doors are mounted beneath the axle hoods and upon pivot rod 38 supported at its ends in spaced straps 40 located within and welded or otherwise fastened to the axle housings. Each of these latch mechanisms consists of a pair of latches or hooks H of angle or inverted L formation pivotally mounted on the rod 38 and with the leg 44 extending above the axle. This leg 44 is made of sufficient weight as to insure the movement of the end downwardly into contact with the door flange directly above the axle. The long arm of the angle shaped latch hook is formed with an upwardly and forwardly inclined surface 45 merging into an upwardly and rearwardly inclined door supporting surface 46 and these surfaces are projected to one side of the hook arm to form a lug having a back substantially vertical surface 48. This back substantially vertical surface 48 is adapted to contact with a forward substantially vertical surface 50 formed on the latch bolt B. This latch bolt is formed with a vertically elongated slot 52 by means of which the bolt may be mounted on the pivot rod 38 for vertical sliding movement. The bolt is also formed with a ramp engaging nose or lower end 54 tied to and braced by a rib 55 upon either side of which are provided pockets 56 adapted to receive the projections formed on the side of the latch hooks when the latch hooks are in door opening position. The latch bolts are also formed on one or more sides with projecting ears 58 adapted to be engaged by lugs 60 welded or otherwise secured to the hinge portion of the next following or rearward door. These lugs are so positioned that when the door is in open position, as shown in Fig. 6, they will bear against the projecting ears 58 and retain the latch bolt in raised position preventing its dropping down beyond the projections on the latch hooks. If the latch bolt should for any reason drop down after releasing its associated door, it will be lifted again by the lug when the next adjacent door swings to open position.

The latch mechanism for the rear edge of the rearmost door is of slightly modified form as clearly shown in Figs. 1, 9 and 10. In this form the latch hooks are pivoted on rod 62 carried by the end structure and upon which is mounted for vertically sliding movement a latch bolt B identical to that just described. The latch hooks have the door engaging surfaces and bolt engaging surfaces identical with those formed on the hooks just described but in order to insure operation of this latch to a door engaging position, it is formed with a projecting finger 65 spaced upwardly slightly above the door supporting surface 46. In this form when the latch is in door released position, as shown in Fig. 9, the weight of the latch hooks tends to swing them toward the end sill with the projections entered in the pockets of the latch bolt and retaining such bolt in its raised position. When, however, the closing door, as indicated in Fig. 9, swings upwardly the free edge will strike finger 65 and rotate the

latch hooks out of the bolt pocket and bring the surface 46 into engagement with the lower surface of the door, thus permitting the latch bolt to drop down into its position as indicated in Figure 1 with the surfaces 48 of the projection bearing against the surface 50 of the latch bolt. In this manner the latch hooks cannot move toward door releasing position and the latch bolt is held in position by gravity. The operation of the latch mechanisms located adjacent the axles is very similar to that just described with the exception that the latch hooks, due to their counter-weighted ends 44, are always urged toward a door supported position, which would permit the latch bolts to drop if it were not for the retaining lugs 60 supporting the ears 58. In this form of the mechanism as the door swings toward closed position, as indicated in Fig. 6, the door edge strikes surface 45 of the latch hooks causing the same to rotate on the supported axis until such time as the door is lifted above the hook permitting the counter-weight to urge the hook toward the door with surface 46 engaged beneath the bottom surface of the door edge. Shortly after the latch hooks have assumed this position the next rearward door will have started moving upward on the closing ramp (not shown) and the lugs 60 will move away from ears 58 permitting the latch bolt to drop into position with its surface 50 in engagement with the surface 48 of the latch hook projections.

As the car with the improved latches is moved toward the dumping position and in the direction as indicated by the arrows, Figs. 3 and 6, the tripping ramp R will be moving relative to the car in the trough like corrugation formed in the doors and as soon as the latch bolts strike this ramp they will be lifted upwardly causing the latch bolt to release the latch hooks and permit the door to drop onto the ramp where it will be supported until the ramp terminates permitting the door to swing downwardly into the dumping station releasing the coal or other material. Thus it will be seen that the doors are supported by independent latches independently operable and that no portion of the latch mechanism projects beyond the clearance limits of the car alone. In other words, there is no part of the latch mechanism projecting into an area where it may be broken by striking any track structure. It will also be seen that the latches can only be operated by a special ramp properly located with respect to the rails upon which the car runs.

The latch mechanisms as shown and described will operate to release the doors from front to rear of the car. In other words, in one, two, three order, but if it is desired that the doors operate in the three, two, one order, as do most of the doors on cars as now used, such operation can be obtained by eliminating the lower portion of the latch bolts appearing adjacent the axles, in which case the ramp will trip the rearmost latch bolt releasing door 26 and it will in turn as it swings downward bring lug 60 into engagement with ear 58 lifting the bolt and permitting the latch hooks to release the next forward door. In certain mines the service may be such that it may be considered possible for the latches to be accidentally released and under such conditions it may be advisable to duplicate the latches at each position, necessitating the pressing of an additional trough or troughs in the door. In other words, the latch mechanisms shown and described may be duplicated transversely of the car requiring that all latches trans-

versely of the car must be released before the door held thereby can be released.

While the invention has been described more or less in detail, it is obvious that various modifications and arrangements of parts, other than those shown and described, may be made and all such modifications and rearrangements of parts are contemplated as will fall within the scope of the appended claims which define my invention:

What is claimed is:

1. In a drop bottom car, a plurality of hinged bottom doors adapted to swing to open position by gravity, and means for holding said doors in closed position comprising an independent latch mechanism for each door and carried by the car structure adjacent the door edge remote from the door hinge, said latch mechanisms being located entirely and immediately adjacent the longitudinal center line of the car and wholly above the lowermost horizontal plane through the doors, said doors being so constructed and arranged with respect to the latch mechanisms as to permit operation of said latch mechanisms by means arranged externally of the car.

2. In a drop bottom car, a plurality of hinged bottom doors adapted to swing to open position by gravity, and means for holding said doors in closed position comprising independent latch mechanism for each door and carried by the car structure adjacent the door edge remote from the door hinge, each latch mechanism consisting of a pair of spaced pivotally mounted latch hooks engaging the door and a vertically sliding bolt located between and normally preventing pivotal movement of the latch hooks.

3. In a drop bottom car carried on wheels and axles and having a rigid frame joined together by end structures and axle housings, a plurality of hinged bottom doors adapted to swing to open position by gravity, and means for holding said doors in closed position comprising independent latch mechanisms for each door carried solely by the axle housings intermediate the wheels, each of said independent latch mechanisms including a plurality of pivotally mounted counterweighted latch hooks and being located wholly above a horizontal plane through the lowermost portion of the doors, said doors being so constructed and arranged with respect to the latch mechanisms as to permit operation of said latch mechanisms by means arranged externally of the car.

4. In a drop bottom car carried on wheels and axles and having a rigid frame joined together by end structures and axle housings, a plurality of hinged bottom doors adapted to swing to open position by gravity, and means for holding said doors in closed position comprising, independent latch hooks for each door, certain of said hooks being swingably mounted within said axle, housings, and vertically slideable latch bolts carried by said housings and movable downwardly to a position preventing swinging movement of the associated latch hooks.

5. In a drop bottom car carried on wheels and axles and having a rigid frame joined together by end structures and axle housings, a plurality of hinged bottom doors adapted to swing to open position by gravity, and means for holding said doors in closed position comprising, independent latch hooks swingably mounted on said axle housings, counterweights on said latch hooks constantly urging said hooks toward door engaging position, vertically slideable latch bolts car-

ried by said housings and movable into and out of a lowermost position preventing swinging movement of the associated latch hooks.

6. In a drop bottom car carried on wheels and axles and having a rigid frame joined together by end structures and axle housings, a plurality of hinged bottom doors adapted to swing to open position by gravity, and means for holding said doors in closed position comprising, independent latch hooks swingably mounted on said axle housings, counterweights on said latch hooks constantly urging said hooks toward door engaging position, vertically slideable latch bolts carried by said housings and movable into and out of a lowermost position preventing swinging movement of the associated latch hooks, projections on said latch bolts, and lugs on the hinged edge portion of the adjacent door engageable with the projections of the adjacent bolt to hold said bolt in raised position when said adjacent door is in open position.

7. In a drop bottom car carried on wheels and axles and having a rigid frame joined together by end structures and axle housings, a plurality of hinged bottom doors adapted to swing to open position by gravity, and means for holding said doors in closed position comprising, independent latch hooks swingably mounted on said axle housings, counterweights on said latch hooks constantly urging said hooks toward door engaging position, vertically slideable latch bolts carried by said housings and movable into and out of a lowermost position preventing swinging movement of the associated latch hooks, and means to retain said latch bolts in raised position and out of locking engagement with said latch hooks when said doors are in open position.

8. In a drop bottom car carried on wheels and axles and having a rigid frame joined together by end structures and axle housings, a plurality of hinged bottom doors adapted to swing to open position by gravity, and means for holding said doors in closed position comprising, independent latch hooks swingably mounted on said axle housings, vertically slideable latch bolts carried by said housings and normally locking said latch hooks in door supporting position and being movable vertically a predetermined amount to permit swinging of said latch hooks to door releasing position, said latch bolts having their lowermost portion located above a plane through the lower portion of said doors when closed, and means formed in said door permitting operation of said latch bolts by a ramp positioned between the rails upon which the wheels run.

9. In a drop bottom car carried on wheels and axles and having a rigid frame joined together by end structures and axle housings, a plurality of hinged bottom doors adapted to swing to open position by gravity, and means for holding said doors in closed position comprising, independent latch hooks swingably mounted on said axle housings, vertically slideable latch bolts carried by said housings and normally locking said latch hooks in door supporting position and being movable vertically a predetermined amount to permit swinging of said latch hooks to door releasing position, said latch bolts having their lowermost portion located above a plane through the lower portion of said doors when closed, and means formed in said door permitting operation of said latch bolts by a ramp positioned between the rails upon which the wheels run, said last named means comprising a downwardly open corrugation forming an inverted trough of a

depth at least equal to said predetermined amount of movement of said latch bolts.

10. A latch for a drop bottom door on mine or similar cars comprising, a vertically slideable latch bolt, recesses formed in said bolt at either side thereof, spaced apart latch hooks swingably mounted for movement into and out of engagement with the door, and projections formed on said hooks and extending into said recesses when the bolt is raised to permit swinging of the latch hooks to door releasing position.

11. A latch for a drop bottom door on mine or similar cars comprising, a vertically slideable latch bolt, recesses formed in said bolt at either side thereof, spaced apart latch hooks swingably mounted for movement into and out of engagement with the door, and projections formed on said hooks and extending into said recesses when the bolt is raised to permit swinging of the latch hooks to door releasing position, said projections

normally engaging portions of said latch bolt to prevent swinging of said hooks whereby the door is retained in closed position.

12. A latch for a drop bottom door on mine or similar cars comprising, a vertically slideable latch bolt, recesses formed in said bolt at either side thereof, spaced apart latch hooks swingably mounted for movement into and out of engagement with the door, and projections formed on said hooks and extending into said recesses when the bolt is raised to permit swinging of the latch hooks to door releasing position, said latch hooks being so formed and arranged as to retain said bolt in raised position when said projections are extended into said recesses and being provided with means engageable by the free edge of the door during closing movement to swing said hooks to door engaging position.

VICTOR WILLOUGHBY.
